UNITED STATES PATENT OFFICE.

CLABEORN P. RANDOLPH, OF LOS ANGELES, CALIFORNIA.

VEHICLE-SPRING.

1,194,423.

Specification of Letters Patent. Patented Aug. 15, 1916.

Application filed May 11, 1914. Serial No. 837,615.

To all whom it may concern:

Be it known that I, CLABEORN P. RANDOLPH, a citizen of the United States, residing at Los Angeles, in the county of Los Angeles and State of California, have invented a new and useful Vehicle-Spring, of which the following is a specification.

This invention relates to vehicle springs, and the main object of the invention is to provide a spring which is so constructed that it cushions both the up and down movements of the vehicle, and acts to absorb the shock in both directions, so that the shock absorbers are unnecessary.

15 A further object is to provide for an accumulative cushioning action in either direction.

Referring to the drawings: Figure 1 is a side elevation of one form of the spring. Fig. 2 is an enlarged section on line x^2-x^2 , Fig. 1. Fig. 3 is an enlarged section on line x^3-x^3 , Fig. 1. Fig. 4 is an enlarged section on line x^4-x^4 , Fig. 2. Fig. 5 is a perspective of a portion of the buckle and roller support. Fig. 6 is a front elevation of a spring to be employed on the front end of the vehicle. Fig. 7 is a side elevation of another form of spring. Fig. 8 is a side elevation of another form of spring. Fig. 9 is a front elevation of a spring for the front of the vehicle. Fig. 10 is a side elevation of another form. Fig. 11 is a perspective of an adjustable strap fastening.

In the form shown in Fig. 1, the spring 35 comprises three sections, an upper section a , a middle section b and a lower section c . The upper spring section comprises several leaves 1 bowed upwardly, and all of the leaves of the three sections are secured at 40 the center by a clip 2, which is the axle support. The upper leaf of the section a has an eye 3 at each end thereof for attachment to the frame not shown. The middle section b is composed of a couple of leaves 4 which 45 are bowed upwardly, and the upper leaf has a rounded end 5 and the strap 6 passes thereover and is riveted at 7 to the leaf, the rivet 7 also serving to attach a leather buffering shield 8, which prevents the leaves of the 50 upper section from striking or chafing the strap 6. The strap 6 extends down and around a roller 9, which is mounted on two arms 10 of a plate 11 shown in detail in Fig. 5, which is riveted to the lower leaf 12 55 of the section c , the leaves of the section c being downwardly bowed, and the plate 11

has two depending arms 13 in which is pivoted a tongue 14 having a spur 15 which is adapted to indent the strap to hold the same from slipping, and another spur 16 to indent the strap near the end thereof, so that the tension of the strap will act against the spur 15 to hold the tongue 14 with its spur forced inwardly into the strap and holding the strap against the bottom leaf 12. From 60 the roller 9 the strap 6 passes upwardly over a roller 17 carried by a hanger 18, which is suspended by a roller 19, which rests on top of the upper leaf 1, and the upper leaf is provided with a projection 20 on its upper 65 surface near its end to limit the inward rolling movement of the roller 19.

The parts normally stand as shown in Fig. 1, the upward pressure of the upper spring section a acting upwardly against roller 19 70 to hold the same at some distance away from the projection 20 and holding the strap 6 taut, the lower section 12 resisting upward movement of the lower end and loop of the strap, and the middle section b exerting an 75 upward tension so that all three sections of the spring combine to normally hold the strap under tension sufficient to keep it taut, and the two sections b and c oppose the section a . Upon a downward movement of the 80 frame of the vehicle with respect to its axle, the upper section a is caused to straighten somewhat, its ends moving downwardly and having a tendency to loosen the straps 6, which slack, however, is immediately taken 85 up by the sections b and c , both of which increase their curvature, their normal tension being sufficient to permit this, so that the downward movement of the vehicle is cushioned by the upper section a . If this 90 movement is sufficient to cause the ends of the section b to touch the section a , the straps 6 are prevented from injury or from wear by the protecting shield 8. Upon the rebound and upward movement of the body, as 95 the ends of the upper section a move upward, they draw up rollers 17, and this elongates the loop of each strap 6, which is engaged by the roller 17 and results in shortening the 100 loop of the strap, which engages the roller 9, which results in drawing the lower sections b and c closer together, and the latter therefore act jointly to resist the upward rebound. Any desired adjustment of tension is secured 105 by means of the strap 6, which may be adjusted by means of the tongue 14, greater tension being secured by shortening the strap 110

6, and less tension being secured by loosening the strap.

In the form shown in Fig. 6, the three sections a' , b' and c' are secured at the center.

- 5 The upper section a' is equipped as in the previous form and supports roller 19^a carrying hanger 18^a , the latter having roller 17^a , which supports the loop of the strap 6^a , which in the present form has but a single 10 loop, one end being secured to the middle section b' by rivet 7^a and raised over rounded end 5^a , which is protected by shield 8^a . The other end of the strap 6^a is secured by tongue 14^a to an arm 21, which is rigid with the 15 arm 22. A downward movement of the body of the vehicle is imparted directly to the three sections a' , b' and c' , the lower ends of the section c' being supported by the pivoted arms 22 and moving outwardly as the lower 20 section is depressed. This movement slackens the strap 6^a , which permits expansion of sections a' and b' . During the upward movement, the strap 6^a draws the ends of sections a' and b' toward each other and cushions this movement.

- In the form shown in Fig. 7, the center section b' is pivoted at 27 directly to the frame 28, and the end of the strap 6^b is secured by the adjustable fastening 14^b to the 30 section b' . The strap 6^b then passes upwardly over roller 17^b , which is mounted on the frame 28. The strap then passes down and under roller 5^b , which is mounted on the upper end of a hanger 29, the lower end of 35 the hanger being pivoted at 30 to the lower section c' , there being a buffer shield 8^b to strike the center section b' . The end of the strap is secured to the upper section a' . The downward movement of the frame 28 de- 40 presses the section b' and slackens the strap 6^b , which slack is immediately taken up by sections a' and c' . On the upward movement of the frame as the center section b' is brought upwardly, the roller 17^b elongates 45 the loop which it engages in strap 6^b and acts through the medium of hanger 29 to draw both the upper section a' and lower section c' toward each other, so that these two sections act to cushion the upward stroke.

- 50 In the form shown in Fig. 8, one end of the strap 6^c is connected with the adjustable fastening 14^c to the lower section c^2 , and then passed up over roller 17^c , which is suspended by hanger 18^c on section a^2 , and then passes 55 down and under roller 5^c , which is mounted on hanger 29^c , the lower end of which hanger is pivoted at 30^c to the lowest section d^2 . From the roller 5^c the strap passes upward and is connected to the end of the section b^2 . 60 8^c designates the buffer shield. In this form downward movement of the frame is restricted by the sections a^2 and c^2 , which are moved toward each other and slacken the strap 6^c , the slack being immediately taken up by the 65 expansion of the sections b^2 and d^2 . Upon

the upward movement of the frame as the sections a^2 and c^2 move apart, they draw on the strap 6^c in such a manner as to lift the hanger 29^c and thereby draw the sections b^2 and d^2 closer together, so that the upward 70 movement is cushioned by the sections b^2 and d^2 .

In the form shown in Fig. 9, the upper section a^3 is secured at each end by hangers 31, which are pivoted to the frame 28^d and 75 hangers 18^d and rollers 19^d are mounted on the section a^3 and support rollers 17^d over which the strap 6^d passes, the lower end of the strap being secured by adjustable connection 14^d to the lower section c^3 , and hanger 29^d engages the lower section c^3 and has a roller 5^d under which the strap 6^d passes, the strap then passing upwardly and being connected to the section b^3 . In this form downward movement of the frame causes flattening of the sections a^3 and c^3 and slackening of the strap 6^d , which slack is taken up by the expansion of the section b^3 . Upon the upward movement of the frame, the sections a^3 and c^3 expand, and the section b^3 is drawn 85 by the strap 6^d toward the section c^3 , so that the section b^3 cushions the upward movement of the frame.

In the form shown in Fig. 10 the upper section a^4 is pivoted at the front end direct to the frame 28^e and at the rear end by a hanger 31. A link 32 at the front end of frame 28^e is connected at 33 with a bell crank lever 34, the latter being pivoted at 35 to the front end of the bottom section c^4 , and the arm 36 of the lever being connected with a hanger 37 having a roller 38 which bears on the top of the center section b^4 , the center section having a projection 39 to limit the movement of the roller 38. 8 ^{e} is 100 the buffer. In this form no strap is employed, and upon downward movement of the frame the shock is cushioned by the section a^4 . During the upward stroke the bell crank lever is tilted in a direction to draw down the section b^4 , and at the same time to draw up on the section c^4 , so that both sections b^4 and c^4 act to resist and cushion the upward movement. The adjustable strap fastening 14^b is shown in detail in Fig. 11, 110 and this fastener is similar to the fasteners 14^a and 14^d heretofore mentioned.

What I claim is:

1. In a spring, a plurality of sections, a strap connected at one end to one of said sections, said strap being loosely connected with the other sections with its end secured to one of the latter sections.

2. A spring comprising a plurality of sections, a strap with its ends connected to two different sections, and rollers connected with certain of the sections and engaging intermediate portions of said strap.

3. In a spring, a plurality of sections, a strap having its ends connected to different 130

sections, a buffer over one end connection to shield the strap from the adjoining section, and rollers carried by certain of the sections engaging portions of the strap intermediate 5 its ends.

4. In a spring, a plurality of sections, a hanger with a roller pressed against one of said sections, said latter section having a projection for limiting the position of said 10 roller, said hanger provided with another roller, a strap connected at its ends to certain of said sections and passing over the second named roller.

5. A spring comprising a plurality of sections, a strap fixed at one end to one of said sections, means adjustably securing the other end of the strap to another section, and means on certain of the sections for engaging 15 intermediate portions of the strap.

20 6. In a spring, a plurality of sections, a strap with its ends connected to certain of said sections, a plate provided with up-

turned arms and downturned arms, a roller carried by one pair of arms, said plate being riveted to a section, a tongue pivoted in 25 the other pair of arms, a strap adjustably connected with said tongues and passing over said roller, and a roller carried by another section, over which the strap passes.

7. In a spring, a plurality of sections 30 mounted in the same plane and secured to one another intermediate their ends, and a pair of flexible elements each being fastened at its ends to the ends of two of the sections and being slidably connected intermediate 35 its ends with the other of the sections.

In testimony whereof, I have hereunto set my hand at Los Angeles, California, this 27 day of April 1914.

CLABEORN P. RANDOLPH.
